Patented Jan. 18, 1966

203,503

SOCKET MEMBER FOR A TUBULAR LIGHT

Harry John Dell, Camp Hill, Pa., assignor to AMP Incorporated, Harrisburg, Pa.

Filed Mar. 5, 1965, Ser. No. 84,100

Term of patent 14 years

(Cl. D26—1)

FIGURE 1 is a front, top and right side perspective view of a socket member for a tubular light, showing my new design;

FIGURE 2 is a front elevational view;

FIGURE 3 is a rear elevational view;

FIGURE 4 is a right side elevational view, the left side being substantially a mirror image thereof;

FIGURE 5 is a top plan view; and

FIGURE 6 is a bottom plan view thereof.

I claim:

The ornamental design for a socket member for a tubular light, as shown and described.
